UNITED STATES PATENT OFFICE.

HARRY E. CAMPBELL, OF NEW YORK, N. Y.

SPRING SUSPENSION DEVICE FOR WINDOW-SASHES.

1,191,662.

Specification of Letters Patent. Patented July 18, 1916.

Application filed May 1, 1916. Serial No. 94,566.

To all whom it may concern:

Be it known that I, HARRY E. CAMPBELL, a citizen of the United States, residing at New York, in the county of New York and State of New York, have invented a certain new and useful Improvement in Spring Suspension Devices for Window-Sashes, of which the following is a specification.

The invention is a spring suspension device for window sashes which will counterbalance a sash of any weight within practical limits.

Hitherto it has been the practice to construct a spring of definite and fixed resiliency for each sash of given weight. In my device the suspension springs are all alike, and the user by the means set forth initially and once for all adjusts each spring to counterbalance the weight of the sash which it is to carry.

My suspension device is preferably arranged in a box lintel, and with said lintel may be supplied to the market as a unitary structure. In practice, a builder, for example, may order as many frames as he needs, including the suspension devices, without regard to the differences in the weights of the sashes, knowing that he can adjust said suspension devices to counterbalance whatever differences may exist in said weights.

In the accompanying drawings—Figure 1 is a vertical section through the lintel, one of the jambs, the sashes and the sill of the frame on the line 1, 1 of Fig. 3. Fig. 2 is a vertical section of the lintel and upper portion of one of the jambs, and of the upper sash, on the line 2, 2 of Fig. 3. Fig. 3 is a horizontal section on the line 3, 3 of Fig. 2. Fig. 4 is a horizontal section of the lintel on the line 4, 4 of Fig. 2. Fig. 5 is a vertical section on the line 5, 5 of Fig. 4, the ratchet disk being removed. Fig. 6 is a vertical section on the line 6, 6 of Fig. 4.

Similar letters and numbers of reference indicate like parts.

The frame includes a box-shaped lintel 9, hollow jambs 10 and 11, the lintel and sill being connected by bolts 12. Within the frame are the upper and lower sliding sashes 13, 14. Each sash is suspended by two cords, tapes or chains 15, secured to flanged drums 16, 17. On the outer side of each drum is a journal having its bearing in a concave block 18 within the lintel 9. On the inner side of each drum is a V-shaped

support 19, which supports receive the ends of shafts 20, 20* of polygonal cross section. Said shaft ends are secured in said supports by covers 21 and stirrups 22 which pass under said supports. The arms of said stirrups extend through openings in said covers and receive nuts on their threaded ends. This arrangement of polygonal suspension shaft secured to supports journaled in the lintel is substantially the same as set forth in U. S. Patent No. 1,171,168, granted to me February 8th, 1916.

Secured to the top wall of the lintel in any suitable way, or, if desired, formed integral therewith, is a cross bar 23, Fig. 6, having three downwardly depending legs 24, 25, 26. Between the legs 24, 25 is disposed a ring A, Fig. 5, and between the legs 25, 26 is a similar ring B. Secured on the ring A and on opposite sides of the legs 24, 25 are ratchet disks C, D. Secured on the ring B and on opposite sides of the legs 25, 26 are similar ratchet disks E, F. The rings A, B are retained between the legs 24, 25, 26 by a bar 27 secured to the lower end of leg 25 and extending below said rings. On one side of bar 23 is pivoted a pawl G which engages with the ratchet teeth on disk E, and on the other side of bar 23 is pivoted a pawl H, dotted lines Fig. 5, which engages with the ratchet teeth on disk D.

The polygonal shafts 20, 20* pass through the circular openings in rings A, B, as shown in Fig. 5, and turn freely in said openings, and also in the openings in the disks, so that said disks and rings are not rotated by said shafts. A helical spring I having one end extending through an opening in disk C and secured in ring A incloses the shaft 20 and has its opposite end secured to a collar J fixed on said shaft. A like helical spring K is similarly combined with ring B and collar L on shaft 20*.

At the time the upper sash 13 is raised into closed position, the spring K is in its expanded state, as shown in Figs. 2 and 4, the suspension cords being wound upon their drums. When the upper sash 13 is moved downwardly, said cords rotate the drums and hence the shaft 20*, and because the spring K is attached at one end to the collar L on said shaft and at the other end to the ring B, which is prevented from rotating by the engagement of pawl G with ratchet disk E, said spring is wound up and acts as a

- counterpoise for the weight of the sash. When the sash 13 is raised to close it, the spring K expanding rotates shaft 20*, thus causing the drums to wind up the cords. At 5 the time the lower sash 14 is lowered to closed position, the spring I is in wound up state, as shown in Fig. 4, and counterpoises the weight of the sash, the suspension cords then being unwound from their drums.
- 10 When said sash is raised to open it, the spring I expanding rotates the shaft 20, thus causing the drums to wind up the cords.
- In order to adapt my spring suspension device to sashes of different weight, all that 15 is required is initially to adjust the tension of the helical spring to counterpoise the weight of any given sash. For this reason, I provide the ratchet disks F and D, to which, since they have no engaging pawls, 20 a wrench may easily be applied. By rotating the disk D in direction to cause the teeth of its associated disk C to run under pawl G, I wind up and so increase the tension of spring I, and said spring in turn rotates shaft 20 and drums 16, 17 thereon to cause the cords to pull upwardly on sash 14 until the desired balance is attained. In similar 25 manner, the disk F is rotated to balance sash 13. This adjustment of the spring tension need be made but once for all, when the sashes are put in place in the window-frame.

I claim:

1. A frame, a sash vertically slideable in said frame, a spring suspension device for 35 said sash comprising a shaft and a helical spring surrounding the same and connected at its ends respectively to said shaft and said frame, independently supported means inclosing and rotatable on said shaft for adjusting the tension of said spring, and means for retaining said last-named means in adjusted position.

2. A frame, a shaft journaled in the upper member thereof, a helical spring surrounding said shaft having one end secured to said frame, a support on said frame, a ring connected to the other end of said spring, said ring being loose on said shaft and rotatable in said support to adjust the tension 50 of said spring, means for retaining said ring

in adjusted position, a sash vertically slideable in said frame, and suspension cords connecting said sash to said shaft.

3. A frame, a shaft journaled in the upper member thereof, a fixed support on said upper member, a ring loose on said shaft received and rotatable in said support, a ratchet disk fast on said ring, a pawl on said support engaging said ratchet disk, a helical spring surrounding said shaft having one end secured to said frame and the other end secured to said disk, winding drums on said shaft, a sash vertically slideable in said frame, and suspension cords connected to said drums and said sash.

4. A frame, a sash vertically slideable in said frame, a support disposed at right angles to and secured upon the upper member of said frame, a ratchet disk rotatably secured on said support, a pawl engaging said disk, the said disk and support having openings, a shaft journaled on said upper frame member and passing through said openings, a helical spring surrounding said shaft and connected at one end to said ratchet disk 75 and at its opposite end to said shaft, drums on said shaft, and suspension cords connected to said sash and said drums.

5. A frame, comprising a lintel in closed box form, a transverse partition in said 80 lintel having a recess on its under side, a ring in said recess, ratchet disks having central openings secured on opposite sides of said ring, means for retaining said ring in said recess, a pawl on said partition engaging one of said ratchet disks, a shaft journaled in said lintel and passing through said disks and ring, a helical spring connected at one end to one of said disks and surrounding said shaft and connected at its opposite 85 end to said shaft, drums on said shaft, a sash slideable in said frame, and suspension cords connected to said sash and said drums.

In testimony whereof I have affixed my signature in presence of two witnesses.

HARRY E. CAMPBELL.
